Viktor Schreckengost and Frank G. Alborn,
Cleveland, Ohio, assignors to The White Motor Company, Cleveland, Ohio, a corporation of Ohio

Application August 22, 1934, Serial No. 53,025

Term of patent 14 years

To all whom it may concern:

Be it known that we, VIKTOR SCHRECKENGOST and FRANK G. ALBORN, citizens of the United States, residing at Cleveland, in the county of Cuyahoga and State of Ohio, have invented a new, original, and ornamental Design for a Motor Vehicle Cab, of which the following is a specification, reference being had to the accompanying drawing, forming part thereof,

We claim:

The ornamental design for a motor vehicle cab, as shown.

VIKTOR SCHRECKENGOST,
FRANK G. ALBORN.
